ATTORNEY

UNITED STATES PATENT OFFICE.

WALTER GOODCHILD, OF WYOMING, NEW JERSEY.

REFLECTOR FOR INCANDESCENT LAMPS.

SPECIFICATION forming part of Letters Patent No. 634,295, dated October 3, 1899.

Application filed February 11, 1899. Serial No. 705,270. (No model.)

To all whom it may concern:

Be it known that I, WALTER GOODCHILD, a citizen of the United States, residing at Wyoming, Essex county, New Jersey, have invented certain new and useful Improvements 5 in Reflectors for Incandescent Lamps, of which the following is a specification.

This invention relates to reflectors used in connection with the bulbs of incandescent electric lights. Among the various forms of reflectors for this class of lamps one is provided by silvering the upper part of the bulb down to a point near the largest diameter of the same, leaving the lower portion of the 15 bulb clear all around. Another construction, which is designed, mainly, for a shade, incloses the upper half of the bulb all around with a shade of colored glass, which is afterward united integrally with the glass of the bulb 20 by heat. These devices perform their functions, but being integral with or inseparably connected with the bulb are necessarily discarded with the bulb when the filament of the latter is burned out.

25 The object of the present invention is to provide a reflector of the form of the downwardly-flared upper part of the bulb and adapted to fit rather snugly about such part of the same, said reflector being supported 30 wholly on the bulb by the downwardly-flaring shape of the latter and having a suitable reflecting-surface, such as a silvered surface, for example.

In the accompanying drawings, which illustrate 35 an embodiment of the invention, Figure 1 is a side elevation of the lamp, the reflector being represented in vertical mid-section. Fig. 2 is a plan view of the reflector detached. Fig. 3 is a side elevation of a slightly-modified form of the reflector on a lamp.

40 A represents an ordinary incandescent bulb, and B the reflector thereon. The ordinary bulbs of these lamps are of substantially the same shape or form and for a given candle-power also of substantially the same size. 45 Of circular cross-section, they flare downward from the metal socket-plug a to about the point x, and the part below or beyond that point is nearly hemispherical.

50 The reflector B is constructed to fit quite snugly over and inclose the upper part of the

bulb; but it may be readily lifted off and replaced, the smaller end thereof being of sufficient size to pass over the socket-plug a. The reflector is supported wholly on the bulb 55 and by contact with its flared surface. At its lower edge the reflector may have a projecting marginal lip b, and the reflecting-surface may extend out and over this lip.

Fig. 3 shows the reflector without the lip 60 b, but constructed otherwise in a similar manner.

Preferably the reflector B will be of glass, as it will then expand and contract under differences of temperature to about the same 65 extent as the bulb; but the invention is not limited in this respect. Other materials not liable to injury by heat may be used, as aluminium, for example. Obviously it should not be unduly heavy.

An advantage of this reflector is that while it is readily removable and may be taken from a discarded bulb and put on a fresh one, thus obviating the loss of a reflector with each bulb, yet it does not require (as do most reflectors) some special form of lamp having means for securing it to the metal socket or plug, as it drops over and is supported entirely on the bulb itself. This adapts it to 75 any ordinary incandescent bulb and also enables it to be produced very economically.

As shown in Fig. 3, the lower edge of the reflector is scalloped and is in a plane at right angles to the axis of the bulb; but these features are not essential. The scallops may 85 be omitted and the bottom edge of the reflector be cut obliquely to the bulb-axis.

Having thus described my invention, I claim—

1. The combination with the bulb of an incandescent lamp, of a light-reflector, which fits snugly but removably over the external surface of the downwardly-flared upper part of said bulb and is supported wholly and directly thereon, substantially as and for the 95 purpose set forth.

2. The combination with the bulb of an incandescent lamp, of a removable reflector B, inclosing and snugly fitting the external surface of the upper, downwardly-flared portion 100 of the bulb, said reflector being supported wholly and directly on the bulb and extend-

ing down about to the point where the bulb is largest in diameter, substantially as set forth.

3. The combination with the bulb A, of an 5 incandescent lamp, of a removable, glass reflector embracing, and housing the bulb, and supported wholly on the downwardly-flaring upper portion of the same, said reflector fitting the outer surface of the bulb and having

an outwardly-turned marginal lip at its lower edge, substantially as set forth.

In witness whereof I have hereunto signed my name, this 9th day of February, 1899, in the presence of two subscribing witnesses.

WALTER GOODCHILD.
